UNITED STATES PATENT OFFICE.

LEONARD LE BARON AND ARTHUR C. HARRELL, OF PENSACOLA, FLORIDA.

AUTOMATIC AIR AND STEAM HOSE COUPLING.

1,359,395.

Specification of Letters Patent. Patented Nov. 16, 1920.

Application filed November 21, 1919. Serial No. 339,675.

To all whom it may concern:

Be it known that we, LEONARD LE BARON and ARTHUR C. HARRELL, citizens of the United States, both residing at Pensacola, 5 in the county of Escambia and State of Florida, have invented certain new and useful Improvements in Automatic Air and Steam Hose Couplings; and we do hereby declare the following to be a full, clear, and 10 exact description of the invention, such as will enable others skilled in the art to which it appertains to make and use the same.

The present invention relates to improvements in automatic air and steam hose couplings for railway cars and the like, and the object thereof is to provide a coupling adapted to make an effective air-tight joint between the coupling heads when the same are in the coupled position and to yieldingly 20 hold such coupling heads close together and to provide improved means for causing the interengagement of the coupling heads.

In the accompanying drawings forming a part of this application, and in which similar reference symbols indicate corresponding parts in the several views:

Figure 1 is a view partly in elevation and partly in section of an improved automatic air and steam hose coupling shown in the 30 coupled position;

Fig. 2 is an end view of one of the coupling cylinders showing the air pipe in section;

Fig. 3 is an end view of one of the couplings;

Fig. 4 is a plan view, partly in section, of the coupling heads shown in the engaged position; and

Fig. 5 is a perspective view of the coupling 40 heads.

Referring more particularly to the drawings, 1 and 2 designate two cylinders secured near the ends of two cars that are coupled together, and 3 and 4 indicate metallic straps 45 for hanging the cylinders to the car bottoms; although it will be understood that these cylinders 1 and 2 may be supported on the under frames or other portions of the cars by the use of other appropriate means.

50 In each cylinder is arranged a coil spring 5, which bears at one end against a fixed head 6 and at its other end against a reciprocating piston or plunger 7. The spring 5 tends to constantly and yieldingly force 55 the piston or plunger 7 in one direction; in the sectional portion of Fig. 1, the piston

7 being yieldingly projected in a right hand direction, while in the elevational portion of this Fig. 1 the piston in the cylinder 2 is yieldingly forced by its coil spring in a left hand direction. The springs 5 are intended to yieldingly hold the gaskets of the coupling heads in a compressed condition whereby a leak proof joint will be afforded.

Slidable through each of the cylinders 1 and 2 are the sections 8 and 9 of train pipe coupled at their far ends to the brake mechanism of the car in the usual manner, and carrying at their meeting ends the coupling heads. Collars 10 are fixed by set screws 70 11 to the train pipe sections 8 and 9 at one side of the plungers or pistons 7; so that the coil springs 5 may project the train pipe sections and coupling heads by the pistons 75 striking against the collars 10.

Sleeves 12 and 13 surround slidable pipe sections 8 and 9, these sleeves having flanges 14 and 15 which are formed with or otherwise secured to spiders 16 projecting across the inner ends of the cylinders 1 and 2. The 80 arrangement of the spiders 16 leaves the adjacent ends of both cylinders open, so that the pistons or flanges 7 will not compress air, which would interfere with their operation. On the outer ends of the sleeves 12 and 13 are complemental cuffs 17 and 18, each cuff, as indicated in Fig. 3, being of the semi-conical shape indicated, and having grooves 19 therein which are curved or offset substantially in the manner shown for 85 a purpose to be later described. The side walls of the grooves 19 are preferably flanged as indicated at 20.

The grooves 19 are provided with inclined, offset inner portions 21 which connect at 90 their inner ends with horizontally extending grooves 22 made in the sleeves 12 and 13. The grooves 22 in both of the sleeves are in horizontal alignment and are adapted to allow play of the pins engaged therein which 100 results from relative movement between the two cars. The outer ends of the grooves 19 in the cuffs 17 and 18 are flared, as indicated at 23, to provide a wide mouth for engaging and guiding into the grooves, pins 105 24 and 25 which project in substantially diametrically opposite directions from a pair of coupling heads 26 and 27 carried, respectively, by the two pipe sections 9 and 8.

The pipe sections are screw-threaded as indicated at 28 in Fig. 4, and receive there-

on the threaded nuts 29 which are externally screw-threaded to receive the heads 26 and 27. The heads are freely revoluble on the nuts 29 and, as above referred to, 5 carry the pins 24 and 25 on which are placed the ball bearing rollers 30 and 31. These rollers cover the major portions of their respective pins and are adapted to engage the side flanged walls of the sleeves 10 19, 21 and 22, whereby to ease the passage of the pins through the cuffs and sleeves. However, small portions of the pins 24 and 25 at the inner ends thereof, adjacent the coupling heads 26 and 27, are left free and 15 are arranged to be engaged by claws 32 and 33 on the heads 26 and 27. Each claw is diametrically opposite the pin carried by the same head, so that claw 33 on the head 27 is in position to engage the pin 24 on the head 26 when the two heads are brought together and rotated; and in similar manner the pin 25 on the head 27 is engaged by the claw 32 on the other head 26.

The working faces of the claws 32 and 25 33 are curved to conform to the curvature of the pins 24 and 25, and also to admit of the turning movement of the heads as the heads approach each other.

Each head carries a gasket 34 which projects beyond the outer face of the head and 30 is arranged to come in contact with the gasket on the opposite head, the arrangement being such that when the heads are rotated and coupled together the gaskets 34 will 35 be tightly compressed against each other, and thereby insure a leak-proof joint.

The springs 5 in the cylinders 1 and 2 provide for yieldingly maintaining these gaskets 34 in a compressed condition.

40 In use, when two cars are brought together, the rollers 30 and 31 on the pins 24 and 25 are so arranged as to come within the scope of the flaring mouths 23 of the cuffs and be guided thereby into the slots 19. 45 When the rollers on the pins arrive at the inclined offset portion 21 of the slots, the heads 26 and 27 will be caused to rotate in opposite directions, which is the means of engaging the pins 24 and 25 with the respective claws 32 and 33. After the rollers on 50 the pins have arrived at the grooves or slots 22 in the sleeves 12 and 13, the heads 26 and 27 will be coupled together in the manner shown in Figs. 4 and 5, and the gaskets 34 tightly compressed, so that the coupling is quickly effected and there is little likelihood of leakage.

As indicated in Fig. 1, the rollers 30 and 60 31 on the pins 24 and 25 lie in the horizontal slots 22 in the sleeves 12 and 13 an appreciable distance back from the ends of the inclined portions 21, in order that relative movement between the parts may be compensated by the rollers sliding back and 65 forth in the horizontal grooves 22 without

incurring the possibility of such rollers entering the inclined portions 21 which would serve to unlock or partially uncouple the heads 26 and 27 and admit of possible leakage of air.

70 It is obvious that those skilled in the art may vary the details of construction and arrangement of parts without departing from the spirit of our invention, and therefore we do not wish to be limited to such 75 features except as may be required by the claims.

We claim:

1. In an automatic air and steam hose coupling, the combination of adjacent pipes 80 to be coupled, enlarged cylinders surrounding said pipes, said pipes having a slidable fit axially through said cylinders and adapted to project beyond the ends of the cylinders toward one another, the adjacent ends of the cylinders being in open communication with the atmosphere, means at the open ends of the cylinders for providing a bearing through which the pipes may slide, pistons having a loose fit in the cylinders, means 90 on the pipes for engaging the outer sides of said pistons, the pistons being slidably fitted on the pipes, coiled springs in said cylinders normally acting to force the pistons toward one another, sleeves extending from the adjacent ends of the cylinders toward one another, flaring cuffs carried by the ends of the sleeves and being of substantially semi-cylindrical construction, said cuffs being relatively offset whereby to pass one another, 95 said cuffs and sleeves having slots therein, portions of the slots being offset, said slots having flaring mouths at the ends of said cuffs, compressible gaskets at the adjacent ends of the pipe adapted to be brought together and compressed, radially extending pins carried by the ends of said pipes, and hooks extending at right angles to the axis of said pins and carried by adjacent portions of the pipes for engaging about said 100 pins, said hooks having curved bills to cause the drawing together of the pipes and the compression of the gaskets, substantially as described.

2. In an automatic air and steam hose 115 coupling, the combination of a pair of axially slidable pipes, compressible gaskets carried by the adjacent ends of said pipes and adapted to be brought together, radially extending pins carried by the ends of the pipes, 120 hooks carried by adjacent portions of the pipes and adapted to extend about said pins, said hooks provided with curved bills adapted to cause the compression of the gaskets when the pipe sections are turned relatively, 125 rollers carried by the outer portions of the pins, cylinders surrounding the pipe sections inwardly of their adjacent ends, spring means for normally forcing the pipe sections together, semi-cylindrical sleeves ex- 130

tending toward one another from said cylinders and partially embracing said pipes, semi-conical cuffs carried on the ends of said sleeves, and said cuffs and sleeves having 5 offset slots therein adapted to receive said rollers and to cause the partial rotation of the pipes when moved together, substantially as described.

3. In an automatic air and steam hose 10 coupling, the combination of a pair of relatively movable pipes extending in coaxial relation, gaskets carried at the adjacent ends of said pipes and adapted to be compressed when the pipes are brought together, rotatable heads carried by the adjoining ends 15 of the pipes, radially extending pins projecting from diametrically opposite points on said heads, hooks extending at right angles to said pins and also carried at diametrically opposite points on said rotatable heads, 20 said pins and hooks being axially offset, the hooks provided with curved bills taking about said pins when the heads are rotated to cause the heads to be drawn together and

the gaskets compressed, cylinders of large 25 diameter fixedly mounted and surrounding said pipes inwardly of their adjoining ends, coil springs in said cylinders, pistons in said cylinders loosely mounted over said pipes and acted on by said coil springs to move 30 toward one another, means on the pipes engaged by said pistons to yieldingly hold the pipes together, bearing means on the inner open ends of said cylinders, semi-cylindrical sleeves in offset relation partially surrounding 35 said pipes, semi-conical cuffs on the ends of said sleeves, said cuffs and sleeves having slots therein with offset portions in the central parts thereof and with flaring mouths opening at the edges of the cuffs, and rollers 40 carried by the outer ends of said pins for entering the mouths and slots and being rotatable by the offset portions of said slots to cause engagement with the hooks, substantially as described.

LEONARD LE BARON.
ARTHUR C. HARRELL.
